STABILIZED BLASTING EXPLOSIVE
COMPOSITION

Edward Whitworth, West Kilbride, and James C. Hornel, Ardrossan, Scotland, assignors to Imperial Chemical Industries Limited, a corporation of Great Britain

No Drawing. Application January 29, 1946, Serial No. 644,195. In Great Britain March 14, 1945

4 Claims. (Cl. 52—11)

1

The present invention relates to the production of improved blasting explosive compositions of the kind liable on prolonged heating to evolve oxides of nitrogen, and is especially applicable to blasting explosive compositions as aforesaid comprising nitric esters, ammonium nitrate, or metallic nitrates amongst their ingredients, and thus to most of the blasting explosives of commerce. The invention relates more particularly to the stabilization of blasting explosive compositions as aforesaid for storage purposes.

Although various other factors can affect the stability of nitric esters and inorganic nitrates, it is well known that traces of acids adversely affect the stability of explosives containing these ingredients, as evidenced by the increased yield of oxides of nitrogen they evolve when they are heated. Since it is impossible entirely to avoid the presence, or at least to prevent the development, of impurities of acid character in such explosive compositions, small amounts of faintly alkaline substances are frequently included as stabilizers, in explosive compositions of the kind described, for instance chalk or ammonium carbonate. On continued storage, however, much faintly alkaline substances become used up, and they do not prevent the development of acidity and the consequent evolution of oxides of nitrogen from continuing thereafter. The presence of an excessive alkalinity in the explosive composition may also accelerate its decomposition.

It has been proposed in British Patent No. 383,630 to include a small amount of one or more mildly alkaline phosphates in explosive compositions especially in those containing sodium nitrate contaminated with soluble magnesium and/or calcium salts; more particularly disodium hydrogen ortho-phosphate, diammonium hydrogen ortho-phosphate, or sodium ammonium hydrogen ortho-phosphate, and various explosives containing diammonium hydrogen ortho-phosphate have found successful application in practice. The buffering action of these mildly alkaline phosphates satisfactorily prevent the development of acidity and they have a marked stabilizing action. Diammonium hydrogen ortho-phosphate, however, may evolve ammonia when it is heated; and under moist conditions the other mildly alkaline ortho-phosphates may react on heating with ammonium nitrate with the evolution of ammonia. More generally their initial alkalinity is higher than the most desirable level.

We have found that neutral mixtures of alkali metal dihydrogen ortho-phosphates with di-alkali metal hydrogen ortho-phosphates exhibit a desirable stabilizing action when present in ad-

2

mixture with the other ingredients of blasting explosive compositions of the kind described, with the added advantage that their buffering action maintains the explosive composition substantially neutral.

Thus, irrespective of the precise amount of the traces of acid or alkaline impurities that may be present in the other ingredients of the blasting explosive composition, the introduction results in a practically neutral explosive composition.

One advantage of this is that even if the composition contains an ammonium salt such as ammonium nitrate, it will not readily evolve ammonia on heating. Moreover the use of faintly alkaline stabilizers of very low solubility, such as calcium carbonate, or the presence of traces of other alkaline substances will not render the composition appreciably alkaline when the neutral mixture of alkali metal dihydrogen ortho-phosphate and di-alkali metal hydrogen ortho-phosphate used according to the invention is incorporated in the composition. On the other hand, the explosive composition does not develop any appreciable acidity on storage and its stability characteristics are markedly improved.

The invention therefore comprises the inclusion in blasting explosive compositions of the kind liable on prolonged heating to evolve oxides of nitrogen, of small amounts of an alkali metal dihydrogen ortho-phosphate and a di-alkali metal hydrogen ortho-phosphate in relative proportions such as to give a neutral mixture of these salts.

In putting the invention into effect it is preferred to employ a previously prepared neutral mixture of the alkali metal dihydrogen ortho-phosphate and di-alkali metal hydrogen ortho-phosphate. This mixture may conveniently be distributed through one or more of the non-explosive ingredients, if such are present, before bringing these into admixture with the explosive ingredients of the composition, in order to facilitate its distribution throughout the final composition. The alkali metal dihydrogen ortho-phosphate and the di-alkali metal hydrogen ortho-phosphate may if desired be employed each in its customary hydrated crystal form, or in the anhydrous form. An equimolecular mixture of sodium dihydrogen ortho-phosphate, monohydrate and disodium hydrogen ortho-phosphate dodeca-hydrate may be employed, advantageously using about 0.25 to 2.5 per cent of these hydrated salts, reckoned on the total weight of the explosive composition. The potassium salts, which are encountered in the anhydrous form, may also be used in equimolecular proportions in the equivalent percentages.

The resulting explosives may be tested for stability by exposing them in a vacuum at raised temperatures, for instance 60° C. to 100° C., and measuring the amount of gas evolved over suitable periods of time. The invention is illustrated in the following examples, in which the percentages are percentages by weight.

Example 1

A gelatine explosive is made from the following ingredients:

	Per cent
Nitrated 80:20 mixture of glycerine and ethylene glycol	50
Soluble nitrocellulose	2.3
Ammonium nitrate	41.7
Woodmeal	5.5
Equimolecular mixture of sodium dihydrogen ortho-phosphate mono-hydrate and disodium hydrogen ortho-phosphate dodeca hydrate	0.5

The incorporation of the ingredients is carried out by first mixing the nitrated mixture of glycerine and ethylene glycol with the soluble nitrocellulose and allowing the mixture to stand until the nitrocellulose is dissolved. The viscous jelly or solution thereby formed is then transferred to a McRoberts mixer where the woodmeal and a previously prepared mixture of the ammonium nitrate and the mixed ortho-phosphates are mixed into it. When heated in a vacuum stability test at 100° C. 1 gram of the resulting gelatine explosive gives a gas evolution of 3.4 ccs. in 8 hours, 9.7 ccs. in 16 hours and 21.4 ccs. in 24 hours. Its explosive properties are satisfactory. It reacts neutral.

In a similar explosive composition in which there is used an extra 0.5 per cent ammonium nitrate instead of the mixed ortho-phosphates, the gas evolution in the same vacuum stability test at 100° C., was 9 ccs. in 8 hours, 21.2 ccs. in 16 hours, and a volume greater than the maximum volume the apparatus is adapted to measure; that is to say greater than 25 ccs. in 24 hours. This illustrates the superior stability characteristics of the explosive made in accordance with the invention over a closely similar explosive composition not in accordance with the invention.

Example 2

A gelatine explosive is made from the following ingredients:

	Per cent
Nitrated 80:20 mixture of glycerine and ethylene glycol	34.0
Soluble nitrocellulose	1.0
Liquid mixture of dinitrotoluenes	1.8
Ammonium nitrate	35.8
Sodium nitrate	19.0
Woodmeal	7.6
Chalk	0.3
Equimolecular mixture of sodium dihydrogen ortho-phosphate monohydrate and disodium hydrogen ortho-phosphate dodeca hydrate	0.5

A jelly or viscous solution is first prepared from the nitrated mixture of glycerine and ethylene glycol, the liquid dinitrotoluenes and the nitrocellulose, and the remaining ingredients are then introduced into the jelly or viscous solution in a McRoberts mixer without the premixing of these ingredients other than the admixture of the two phosphates with one another. The resulting gelatine explosive is of neutral character and satisfactory explosive properties. It is also of excellent stability.

In the vacuum stability test carried out at 100° C. the volume of gas evolved was 4.2 ccs. in 8 hours, 12.4 ccs. in 16 hours and 21.2 ccs. in 24 hours, whereas from a similar explosive composition made without the mixed phosphates but with an extra 0.5 per cent ammonium nitrate the corresponding gas volumes were respectively 8.6 ccs., 16.2 ccs., and more than 25 ccs.

We claim:

1. A blasting explosive composition comprising a liquid explosive nitric ester, at least one salt selected from the group consisting of ammonium nitrate and a mixture of ammonium nitrate and sodium nitrate, and from 0.25 to 2.5% by weight of a substantially equimolecular mixture of at least one dialkali hydrogen ortho-phosphate and at least one alkali metal dihydrogen ortho-phosphate.

2. A blasting explosive composition comprising a liquid explosive nitric ester, ammonium nitrate, and from 0.25 to 2.5% by weight of a substantially equimolecular mixture of at least one dialkali hydrogen ortho-phosphate and at least one alkali metal dihydrogen ortho-phosphate.

3. A blasting explosive composition as claimed in claim 2, wherein disodium hydrogen ortho-phosphate dodeca hydrate and sodium dihydrogen ortho-phosphate mono-hydrate are present in substantially equimolecular proportions to form the mixture.

4. A blasting explosive composition comprising nitroglycerine, ammonium nitrate, and from 0.25 to 2.5% of a mixture of substantially equimolecular quantities of sodium dihydrogen ortho-phosphate mono-hydrate and disodium hydrogen ortho-phosphate dodeca hydrate.

EDWARD WHITWORTH.
